JEWELRY DISPLAY

Wilson M. Brady, Catonsville, Md.

Application September 17, 1948, Serial No. 49,670

3 Claims. (Cl. 211—13)

1

This invention relates to sales display equipment and more particularly to articles that can be placed on store counters or shelves and window spaces for artistically presenting specific items of a relatively small size, such as jewelry and the like, so they may be observed, conveniently handled and purchased.

It has been customary to display articles and jewelry on counters and the like in individual boxes finished interiorly with plush or velvet, formed with a resilient depression in which part of the ring, pin, clasp or similar item may be inserted and held. The item is removed bodily from the box to show the customer its characteristics and display its attractive qualities. This requires handling of the article itself, its removal and its replacement, in the depression. This handling tends to soil the article, so that from time to time, it is necessary to reclean and polish it. This is expensive and time consuming. Further it requires the handling of the box itself, which is easily soiled and has to be replaced quite frequently. The cost of the box is small but eventually this continual replacement adds up to a considerable sum of money. The box is also conventionally of cubical form which is not as effective as might be desired, since it is laid in a horizontal position, while the onlooker looks at it from an angle, and therefore does not get a direct view of the piece of jewelry held by it. Also there is nothing particularly attractive about the type of box used, excepting that the covering of plush or velvet attracts attention. In this invention, the display unit is in two parts, one of these hold the article to be displayed, while the other is a recessed easel that supports the holder and both together form a substantial unit that will present the article displayed at an attractive angle that may be handled conveniently and effectively. At the same time, the jewelry may be removed intact with the holder and displayed to the customer, without actually touching it. This keeps the jewelry in the setting of plush or velvet that the holder is encased in, and thereby continually holds the article in the comparative field that the plush or velvet provides, before the customer's eyes. The psychological effect of removing the ring, pin, ear ring, pendant, watch, or other article involved on the holder, and holding it up free to the eyes of the customer without the attractive background, is very detrimental. The customer loses the effective influence of the backing and may be depressed sufficiently to lose interest in buying the article. It is somewhat

in effect like the removal of the cosmetics from the features of an up-to-date woman, the woman is attractive but the cosmetics enhance her beauty. It is therefore highly desirable that the attractive makeup on which the article of jewelry is mounted be kept intact during the process of selling it. In addition the holder is arranged so as to be interchangeable and provided with other features that emphatically impress its individuality on the prospective buyer.

For a better understanding of the invention reference is made to the drawings, which illustrate a particular form thereof by way of example. These drawings together with the following description indicate the principles of the invention and more fully explain the objects, while the claims emphasize the scope of the invention.

In the drawings:

Figure 1 is a front view of a jewelry display embodying this invention;

Figure 2 is a side view of Figure 2;

Figure 3 is a sectional view taken along line 3—3 of Figure 1, and

Figure 4 is a modified form of jewelry display. Similar reference numerals pertain to the same parts throughout the drawings.

The construction shown in the drawings, consists of a right-triangular block 10 with one side 11 forming a base on which to rest itself. This 30 provides an angular face 12. A corner of the block is removed at its top, to provide a flat portion 13 parallel to the base 11, and from which the angular face 12 extends downwardly. The face 12 has slightly raised horizontal rectangular members 14 projecting from it at right angles. These members 14 are spaced from each other slightly and are equidistant from a slot 15 in the face 12. The members and slot are so arranged that they form a suitable holder for a conventional ring 35 or similar article. A second part of the unit consists of a flat pad 16 that fits onto the block 10 and is supported thereby by reason of the fact that this pad 16 has an opening 17 therein, the inner edges of which fits frictionally tight against the outer edges of the projections 14 and the adjoining portions of the block 10. The opening 17 being preferably centrally located in the pad and enough area is left for the arrangement of several insignia pins or buttons 18 at the top. A nameplate broach 19 is mounted in the space at the bottom of pad 16, to explain the class to which the various articles on the pad pertain. The buttons 18 are held by their nuts 20 at the 55 back on the screw shanks 21 of same passing

through holes 22 arranged in the pad 16. The pad is preferably made wider than the block 10 to make room for a larger display and partially hide the block. The block and pad are preferably neatly covered with velvet 23 of a bright and attractive color, adequate to show off the jewelry mounted on it. Of course it is appreciated that plastic could be substituted for the velvet or used in other ways, for the unit. The flat portion 43, in back of the pad, facilitates placement of the pins thereon.

In the modified forms of the invention indicated in Figure 4 the same construction is shown in general but the pad is extended to include more area for more articles and nameplate designations. The flat pad 50 is arranged to support a necklace 51, and ear rings 52. The base 10 fits through the rectangular opening 53. The base 10 is the same as that described heretofore, and is provided with a slot 15 to receive the ring 54.

The unit is ordinarily set on a counter in the position shown in the drawings, however when the customer is particularly interested, the salesman, lifts it up without separating the pad 16 from the block 10 and shows the articles thereon without removing them. This he does by holding the pad by its edges. As he does not handle the articles in his fingers but retains them on the pad with its attractive background, he presents the articles in a most effective manner. The nameplate pin indicates to what class the articles belong. Since this pin is in the form of a broach it is attractive and in case of demand can be sold also, and replaced by another. If the pad 16 is considered obsolete at any time, it is readily changeable on the block for another, as the pads would be made in standard types for this purpose. This also allows the pads of one color to be attached to the blocks of another color. Many variations can be made in the arrangements of blocks and pads, the main point being in the provision of an opening to properly fit on the members. Since the block holds the pad at an angle, the latter can always be observed by the looker-on in a natural and facile manner.

While but two general forms of the invention are shown in the drawings and described in the specifications, it is not desired to limit this application for patent to these particular forms or in any other way, as it is appreciated that other forms could be made that would use the same principles and come within the scope of the appended claims.

Having thus described the invention what is claimed is:

1. A display unit for jewelry and the like, comprising in combination, an angularly cut block having projecting members on one face thereof, a pad having an opening therein to allow the pad to be placed on said members and held thereby, said pad being angularly positioned by the block so as to be readily observable from in front and having an area larger than that of the face of the

block on which the pad is placed for the placement of articles of jewelry thereon, said members and opening being of rectangular form to facilitate the placement of the pad in predetermined relation to said members for the display of the articles in a predetermined position, said block having a portion removed from the upper edge to allow access to the back portions of the articles placed on the pad.

- 10 2. A display unit for jewelry and the like, comprising in combination, an angularly cut block having projecting members on one face thereof, a pad having an opening therein to allow the pad to be placed on said members and held thereby, said pad being angularly positioned by the block so as to be readily observable from in front and having an area larger than that of the face of the block on which the pad is placed for the placement of articles of jewelry thereon, said members and opening being of rectangular form to facilitate the placement of the pad in predetermined relation to said members for the display of the articles in a predetermined position, said block having a portion removed from the upper edge to allow access to the back portions of the articles placed on the pad, said block having a recess formed adjacent to the members whereby a ring or the like may be placed therein for display in addition to said articles.
- 15 3. A display unit for jewelry and the like, comprising in combination, an angularly cut block having projecting members on one face thereof, a pad having an opening therein to allow the pad to be placed on said members and held thereby, said pad being angularly positioned by the block so as to be readily observable from in front and having an area larger than that of the face of the block on which the pad is placed for the placement of articles of jewelry thereon, said members and opening being of rectangular form to facilitate the placement of the pad in predetermined relation to said members for the display of the articles in a predetermined position, said block having a portion removed from the upper edge to allow access to the back portions of the articles placed on the pad, said block having a recess formed adjacent to the members whereby a ring or the like may be placed therein for display in addition to said articles, and fabric means placed about the block and pad individually for increasing the effective display of the articles and their attachment thereto.
